ANIMATED TOY

Albert L. Bresch, University City, Mo.

Application September 20, 1945, Serial No. 617,652

10 Claims. (Cl. 46—118)

1

This invention relates generally to toys. More particularly, my invention relates to a certain new and useful improvement in toys of animated musical type and has for its primary object the provision of a toy of the type stated, which is simple and inexpensive in structure, which is conveniently and easily operable, and which is so constructed for the production of various amusing combined visual and sound effects.

And with the above and other objects in view, my invention resides in the novel features of form, construction, arrangement, and combination of parts presently described and pointed out in the claims.

In the accompanying drawing,

Figure 1 is a longitudinal sectional view of an animated musical toy constructed in accordance with and embodying my present invention;

Figures 2 and 3 are sectional elevational views of the toy, taken approximately along the lines 2—2 and 3—3, respectively, of Figure 1, showing the figure of the toy in different positions of animation; and

Figures 4, 5, 6, and 7 are detail elevational views of some of the particular figure-forming elements or members of the toy in disassembled relation.

Referring now in more detail and by reference characters to the drawing, which illustrates a preferred embodiment of my present invention, the toy includes a musical member A preferably, as shown, of plunger-whistle type, which comprises a suitably elongated cylindrical or tubular shell 1 partially cut away and provided at one end with a mouth-piece 2 of conventional design, the shell 1 being formed with a conventional note-emitting aperture 3 and being fitted at its other end with a tight fitting end-plug 4 having an axially extending aperture or bore 5. Disposed for longitudinal shiftable movement relatively to the shell 1 and through the bore 5 of plug 4, is a plunger-rod 6 transversely provided at its inwardly presented end with a plunger 6' diametrically sized for snug fitting slidable engagement with the inner face of the wall of shell 1.

The plunger-rod 6 is also suitably elongated and intermediate its ends is right angularly bent, as at a, to include a downwardly presented portion b and is then doubled upon itself, as at c, to project upwardly partially, as at d, in parallel abutting relation to the portion b in the formation therewith of a rod actuating hand or finger-grip 6', the rod 6 being then continued upwardly in the provision of a support 6'', upon the upper

end of which is mounted for animation the particular figure B of the toy.

Such figure B may be of any suitable contour and configuration, the figure B, in the present instance, being in representation or simulation of an acrobat or clown, commonly designated a jumping-jack, which is built up of and comprises a pair of similarly shaped companion front and rear body-elements in the form of plates 7, 7', respectively, each marginally provided with slots 8 and with outwardly presented tabs 9 having teats 10, the tabs 9 of front section 7 being bent rearwardly to engage the front face of rear section 7' and the teats 10 thereof projected through the slot 8 of, and clinched upon, the rear section 7', and the tabs 9 of rear section 7' being bent forwardly in overlapping relation upon the front section tabs 9 to engage the rear face of front section 7 and the teats 10 thereof projected through the slot 8 of, and clinched upon, the rear section 7', and the tabs 9 of rear section 7' being bent forwardly in overlapping relation upon the front section tabs 9 to engage the rear face of front section 7 and the teats 10 thereof projected through the slot 8 of, and clinched upon, the front section 7 for firmly securing the body-elements 7, 7', together in spaced registering relation. As shown, the rear body section 7' is fixed in upstanding relation upon the upper end of rod-continuation 6'', so that the figure B is bodily movable with the plunger-rod 6, and for purposes presently appearing the body-elements 7, 7', are provided centrally in their upper or chest portion with registering longitudinal slots 11.

30 Pivotedly mounted and secured, as by means of small transverse pins 12, for free swinging movement intermediate the base or lower portion of the body-elements 7, 7', as shown, is a pair of oppositely disposed companion leg-simulative elements 13 disposed in overlapping relation at their upper or thigh-portions and each being provided in its upper or thigh-portion with a suitably disposed slot 14.

Similarly mounted on cross or transverse pins 40 15 for free swinging movement intermediate the upper portion of the body-sections 7, 7', is a pair of oppositely disposed companion arm-simulative members 16, which are likewise disposed in overlapping relation at their inner or shoulder-ends and each being provided at its said upper or shoulder-end with a longitudinal slot 17, the figure B being completed by a head-simulative member 18 pivotally, as by a cross or transverse pin 19, joined to the body-section 7', at the upper or neck end thereof and having a downwardly presented neck-extension 20 provided with a somewhat obliquely extending slot 21. Extending axially upwardly intermediate the body-elements 7, 7', is an actuator in the form preferably of a flat strip 22 provided with a first transversely

disposed pin 23, which operatively works in the slots 14 of the overlapping thigh-portions of the leg-simulative members 13 and with a second transversely disposed pin 24 which similarly works not only in the slots 17 of the overlapping shoulder-portions of the arm-simulative members 16, but also in the slot 21 of the head-simulative member 18, all as best seen in Figures 2 and 3.

It will hence be evident that as the actuator strip 22 is endwise moved downwardly, the legs 13, arms 16 and head 18 of the figure B will "bob" or swing sidewise and upwardly to the respective positions shown in Figure 2, and that, as the actuator strip 22 is endwise moved upwardly, the legs 13, arms 16, and head 18 of the figure B will "bob" or swing in the opposite direction to the respective positions shown in Figure 3.

For effecting such relative swinging movements, the actuator strip 22 has at or adjacent its lower end a somewhat flexible pivoted connection, as at 25, with the outer or free end of an angularly deflected spring or resilient rod 26, which is projected forwardly and suitably fixed or attached at its forward end, as at 27, to and adjacent the forward end of the plunger-rod 6, the rod 26 being arranged for slidably engaging along its upper face and intermediate its ends the upper guiding margin or rim of the aperture 5 in the end-plug 4 of shell 1.

By reference to Figure 1, it will be seen that, when the plunger-rod 6 is shifted by means of the finger-grip 6' rearwardly or outwardly from the shell 1 to the position thereof shown in full lines, the spring-rod 26 will be disposed at its position of greatest angularity away from the rod 6, thereby forcing the figure-actuator strip 22 upwardly. As the plunger-rod 6 is shifted reversely or inwardly into the shell 1, the rod 26 will bear at its upper face against the wall of the end-plug aperture 5, the rod 26 being thereby forced downwardly toward the plunger-rod 6 to the position thereof shown in dotted lines in Figure 1, and accordingly moving the actuator strip 22 downwardly to effect the described relative movements of the several jointed elements of the particular figure B. It will be evident in this connection that the longitudinal movement of the plunger 6 within the shell 1 will vary the pitch of the note emitted thereby and, therefore, following a little practice, a person operating the toy may play simple tunes by sliding the plunger 6 inwardly and outwardly to varied positions, such movements of the plunger 6 simultaneously producing movements of or animating the figure B with a highly amusing and entertaining effect.

The several elements of the figure B may be suitably colored and embellished in furtherance of the particular simulation, and it should, of course, be understood that any suitable type of movable figure may be substituted for the present jumping-jack figure, that other types of similarly operated musical members may likewise be substituted for the particular plunger-whistle here illustrated, and that other changes and modifications in the form, construction, arrangement, and combination of the several parts of the toy may be made and substituted for those herein shown and described without departing from the nature and principle of my invention.

Having thus described my invention, what I claim and desire to secure by Letters Patent is:

1. An animated toy comprising a movable

member, in combination with a figure mounted on and bodily movable with said member, said figure including a body portion and head-simulative swingable element having an angularly slotted neck extension, and means for swinging said element responsive to movement of said member, said means including a strip having a pin working in said slot for producing controlled sidewise swinging movement of the head-simulative element, and a third member having connection at an end to the movable member and pivotally attached at its other end to the strip.

2. An animated toy comprising, in combination, an elongated tubular shell, an axially apertured plug fixed within the shell, a first rod movable longitudinally through the aperture of the plug, a figure mounted on and bodily movable with said rod, said figure including a plurality of relatively swingable elements some of which are disposed in endwise overlapping pair relation, and means for relatively swinging said elements in unison responsive to longitudinal movement of said rod, said means including a strip having slot-and-pin connection with all said elements, and a second rod having connection at an end with the first rod and pivotally attached at its other end to the strip, said second rod having a bearing actuating sliding engagement intermediate its ends with the wall of the aperture of the plug.

3. A toy comprising, in combination, a whistle having a pitch-varying plunger and an apertured end-plug said plunger being provided with an actuating rod extending shiftably through the end-plug aperture, an animated figure mounted on the outer end of the plunger, and means including a resilient rod fixed at one end to the plunger-actuating rod and connected at its other end to the figure for animated actuation thereof responsive to movement of the plunger.

4. An animated toy comprising, in combination, an elongated tubular shell, an axially apertured plug fixed within the shell at one end thereof, a whistle mouth piece formed at the other end 45 of the shell, a first rod movable longitudinally through the aperture, a piston member mounted rigidly on the inner end of said rod for plunger-wise engagement with the shell, a figure mounted on and bodily movable with said rod, said figure including a plurality of relatively swingable elements in the formation of a jumping jack, actuating means operatively connected to said swingable elements for producing movement thereof, and a resilient rod rigidly connected to the first 50 rod interiorly of the shell and extending outwardly through the plug aperture at an angle to the first rod, said resilient rod being operatively connected at its outer end to the actuating means and further having sliding engagement intermediate its ends with the wall of the plug aperture for varying the angle between the resilient rod and the first rod and thereby producing up and down motion of the actuating means responsive to axial movement of the first rod and the 55 associated piston member with respect to the shell whereby the jumping jack will be bodily moved toward and away from the shell responsive to movement of the piston member and the swingable elements will simultaneously be actuated.

5. An animated toy comprising a plunger-whistle having a mouth piece at one end and a plunger handle extending axially from the other end thereof, an animated figure mounted on the handle, and actuating means mounted at one end

on the handle interiorly of the whistle and movable radially toward and away from the handle responsive to plunger-operating movement thereof, said actuating means being operatively connected at its other end to the figure for simultaneously producing bodily and animated movement thereof responsive to movement of the handle.

6. An animated toy comprising a plunger whistle having a mouth piece at one end and a plunger handle extending axially from the other end thereof, an animated figure mounted on the extended end of the handle, actuating means rigidly connected at one end to the handle and extending angularly outwardly therefrom and means on the whistle engageable with the actuating means for shifting said actuating means at its extended end toward and away from the handle responsive to plunger operating movement of the handle, said actuating means being at its extended end operatively connected to the figure for simultaneously producing animated and bodily movement thereof responsive to movement of the handle.

7. An animated toy comprising a plunger whistle having a shell provided with a manually shiftable plunger handle extending axially outwardly therefrom, an animated figure mounted on the handle, and means mounted on the handle and operatively connected to the figure, said means being co-operably engageable with the shell for producing animated movement thereof responsive to plunger operating movement of the handle.

8. An animated toy comprising a plunger whistle having a shell provided with a shiftable plunger handle extending outwardly therefrom, an animated figure mounted on the handle, said figure including a body-portion and a plurality of limb-simulative members swingably mounted on the body-portion, and means mounted on the

5 handle and operatively connected to the limb-simulative members, said means being co-operably engageable with said shell for producing animated movement thereof responsive to plunger-actuating movement of the handle.

9. An animated toy comprising a plunger whistle having a manually shiftable plunger handle extending outwardly therefrom, a movable figure mounted on the handle, actuating means mounted on the plunger handle interiorly of the whistle and extending outwardly from the whistle, being at its outer end operably connected to the movable figure, and means on the plunger whistle operatively engageable with the actuating means for producing figure-motivating movement of the actuating means responsive to tone-varying movement of the plunger handle.

10. A plunger whistle having a mouth piece at one end and an elongated plunger handle extending axially outwardly at the other end, said handle at its outer extremity being bent in the form of a closed U-shaped loop having a projecting leg portion extending transversely across the handle in the formation of a T-end, an animated figure mounted on the end of said projecting leg approximately at eye level when the whistle is held horizontally in the mouth of the user, a plurality of swingable arm and leg-simulative members pivotally mounted on the figure, an elongated link actuating connected to the arm and leg members and extending downwardly therefrom, and actuating means operatively connected at one end of the handle and at the other end to the link and being shiftable toward and away from the handle upon plunger-actuating reciprocation thereof for producing corresponding animated movement of the arm and leg members as the figure is bodily moved toward and away from the whistle.

ALBERT L. BRESCH.
